UNITED STATES PATENT OFFICE

JOSEPH W. MYERS, OF JACKSON, MICHIGAN

PROCESS AND APPARATUS TO BE USED IN PRINTING PHOTOGRAPHS FROM NEGATIVES

Application filed December 19, 1927. Serial No. 241,031.

My invention relates to a process and apparatus to be used in printing photographs from negatives and an object of my improvements is to ascertain the proper time of exposure and the proper grade of sensitive paper to be used and to mark the negative with the data thus ascertained so that the printing can be done correctly by a comparatively unskilled operator.

10 I secure this object in the apparatus shown in the accompanying drawings and by the process hereinafter described.

In the accompanying drawings:-

15 Figure 1 is a plan view of an apparatus embodying my invention.

Figure 2 is a section on the line II, II, Figure 1.

Figure 3 is a detailed section on the line III, III, Figure 1.

20 Figure 4 is a diagram illustrating the various electrical circuits.

a is an enclosed casing, or box, having a slanting top. The walls of said casing are opaque, except for the upper and greater portion of the slanting top, which consists of a glass plate *b* having its surface roughened, or ground.

25 *c* is an electric lamp secured to the rear wall and within the casing *a*. *d* is a concentrating lens located above and axially in line with the lamp *c*, and so constructed that the light rays received by it from said lamp shall be concentrated at *d* at the surface of the plate *b*.

30 *e* represents a negative resting upon the outer surface of the plate *b*.

f is a tube having an opaque wall and having its ends closed. *f* is an opening through the wall of the tube *f* located at such a point

40 that it shall permit the passage of the rays of light which have passed through the lens *d*, the plate *b* and the negative *e*. Within the tube *f* is a conductor *g* of a material such as selenium, the resistance of which varies

45 with the intensity of the light that strikes upon it. The light passing through the aperture *f* falls upon the selenium conductor *g*. The conductor *g* is interposed in a circuit *h*, in which circuit is a sensitive, ammeter *h*, a switch *h*, a variable resistance *h* and a

source of current *h* the voltage of which may be regulated at will by a switch *h*.

m, *m* represent electric mains, *t* a transformer and *r* a variable resistance in circuit with the lamp *c*.

55 *n* is a series of keys located adjacent to the edge of the casing *a* and above the left hand upper corner of the upper surface thereof. *n* is a second series of similar keys located at the side and toward the upper left hand corner of the upper surface of said casing.

60 *j* represents a narrow metal strip secured to the edges of the upper surface of the casing *a* adjacent to the series of keys *n* and *n*. This strip is mainly spaced slightly above the upper surface of the casing so as to permit of a portion of a negative being shoved thereunder. The outer edges of the strip *j* extend beyond the upper surface of the casing *a* and are turned downward, as shown in Figure 3, to form a stop to limit the distance that the edge of the negative may pass under said strip.

65 *k* is a bar having its upper end shaped to form a character, or sign, upon the negative. The bar *k* slides vertically in ways along the side surface of the casing *a* and is actuated by a pivoted lever *k* and retracted by a tension spring *k*.

70 *n* is a bar the lower end of which is pivoted to the outer end of said lever, the upper end carrying the key *n*. There is a bar *k* and connecting mechanism for each of the keys *n* and *n*. The characters printed by actuating the keys *n* may

75 range between the numerals 1 and 10, those upon the keys *n* between 1 and 4.

The operation of the above described device is as follows:

80 The lamp *c* is lighted from the mains, or other convenient source, and the intensity of its light is regulated by the variable resistance *r*.

85 A part of the light from the lamp *c* passes through the glass plate *b* and illuminates the same uniformly and a part of said light passes through the lens *d*, is concentrated at *d* and passes through the aperture *f* falling upon the selenium conductor *g* in the tube *f*.

90 A current is passed through the circuit *h*.

by closing the switch h_3 and this current is adjusted at will by varying the voltage by the switch h_6 , or by varying the resistance in the circuit at h_4 for the purpose of bringing the meter to zero, density reading.

5 The negative is now laid upon the plate b and the lightest and darkest part of the image on said negative is observed and the light part is moved to the point d_2 so that the concentrated rays from the lens d will pass through this part of the negative and strike against the selenium conductor g . The current through the circuit h will now be proportional to the light passing through this 10 point of the negative and its intensity will be indicated by the needle of the ammeter h_2 , which is observed and the edge of the negative at the corner is then passed under the strip j and that key h_2 depressed which shall 15 cause a bar h to print the indication of the needle upon the negative.

The negative is then moved back to its 20 position upon the surface of the plate b and the darkest point of the image upon the negative is observed and the negative is moved until this darkest point is at d_2 and a second 25 reading of the ammeter is made. From this reading is subtracted the first reading—the corner of the negative is placed under the strip j adjacent to a key n_3 which may show 30 the remainder, or the proper paper, and said key is depressed to imprint its character upon the negative, as above described with reference to the keys n_2 .

35 The areas of the said points of the negative the permeability of which are determined must be very small, about the size of a pin in moving picture films and not larger than one eighth of an inch in hand camera 40 films.

The characters upon the scale of the ammeter h_2 are such as to indicate by its needle the seconds and fractions of a second that the negative should be exposed, and, or, density 45 factors of which the exposure is a function, when the light is passing through the lightest part of the image, as above described, and the keys n_2 print this time or factor upon the negative.

50 The grade or sensitive paper that should be used depends both upon the quantity of light passing through the lightest part of the image and the quantity of light passing through the darkest part of the image and 55 the keys n_3 are adapted to indicate this grade of paper when manipulated to correspond to a function of the quantities of light passing through both the lightest and the darkest part of the image on the negative.

60 What I claim is:

1. A process to be used in printing from exposed negatives, consisting in observing the point of the image upon the negative that is most permeable to light, measuring the 65 light-permeability of the negative at said

point, and exposing the negative for a time proportional to said permeability to a grade of paper proper for said negative.

2. A process to be used in printing from exposed negatives, consisting in observing the 70 point of the image upon the negative that is most permeable to light and the point of said image that is least permeable to light, measuring the light-permeability of the negative at each of said points and selecting the sensitive 75 paper to correspond to a function of both of said permeabilities.

3. The combination of an enclosure having a lamp therein, said enclosure being provided with a translucent wall adapted to receive a negative laid flat thereon, said translucent wall being of such a size and so located that the negative may be moved to different positions while lying flat thereon, a concentrating lens in said enclosure adapted to concentrate light from said lamp upon a single point of said wall, corresponding in area to a limited area of the negative in the lightest or darkest part thereof, and means for measuring the intensity of the light passing from 80 said point for the purpose described.

4. The combination of an enclosure having a lamp therein, said enclosure being provided with a translucent wall adapted to receive a negative laid flat thereon, said translucent wall being of such a size and so located that the negative may be moved to different positions while lying flat thereon, a concentrating lens in said enclosure adapted to concentrate light from said lamp upon a single point of said wall corresponding in area to a limited area of the negative in the lightest or darkest part thereof, and means for measuring the intensity of the light passing from 85 said point for the purpose described.

5. The combination of a translucent surface having light passing uniformly therethrough, a negative, said surface being adapted to receive said negative laid flat thereon, said translucent surface being of a size and so located that the negative may be moved to different positions while lying flat thereon, and means for measuring the light-permeability of a desired part of said negative, that is of a very small area relative to the picture of said negative, said part being determined by the movement of said negative, consisting of a special intensity of light passing through one point of said surface registering with said part of said negative and means for measuring the intensity of light passing from 90 said point.

6. The combination of a translucent wall for supporting a negative to be measured, means for directing light through a large part of said wall, means to direct a measuring light ray through a selected point of said wall, and means for measuring the degree of light of said measuring ray.

7. The process of printing a negative, the 95

steps consisting of directing light through a large part of the negative, selecting the point of the negative that transmits the most of said light, measuring the translucency of the selected point in the negative selecting the paper according to the contrast of the negative and exposing said negative for the time indicated by the most translucent point in the negative.

10 In testimony whereof, I sign this specification.

JOSEPH W. MYERS.
